Attorney.

UNITED STATES PATENT OFFICE.

FREDERICK E. SANDBURG, (NOW BY JUDICIAL CHANGE OF NAME FREDERICK E. SANDBURN,) OF BROOKLYN, NEW YORK.

HOLDER FOR DRINKING-GLASSES.

1,276,419.

Specification of Letters Patent. Patented Aug. 20, 1918.

Application filed January 19, 1917. Serial No. 143,370.

To all whom it may concern:

Be it known that I, FREDERICK E. SANDBURG, a citizen of the United States, residing in the borough of Brooklyn, in the county of Kings and State of New York, have invented certain new and useful Improvements in Holders for Drinking-Glasses; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to a drinking glass holder for dental use, proposing a device in the general nature of a bracket for holding the glass in an inverted position to avoid any deposit of dust on its interior surfaces.

The principal objects of the invention are to provide a simple and inexpensive glass holder of the type stated in which the glass is not liable to breakage, may be disinfected, and may be so held as to protect one or more tooth brushes or other dental implements for the support and disinfection of which convenient provision may be made by virtue of the special construction of the holder.

With the above objects in view the holder is provided with means for holding the glass upright and in a definite or invariable relation and with a disinfecting means whose relation to the glass is in consequence of the definite position in which the glass is held and promotes the thorough disinfection of the glass and whose structure is adapted to the support, within the glass, of tooth brushes or other implements which are disinfected at the same time as the glass.

An embodiment of the invention is illustrated in the accompanying drawing, in which—

Figure 1 is a perspective view of the improved holder as in use;

Fig. 2 is a side elevation of the holder showing the disinfecting means in section;

Fig. 3 is a detail sectional view on the line 3—3 of Fig. 2;

Fig. 4 is a detail sectional view on the line 4—4 of Fig. 2;

Fig. 5 is a detail elevation of a guard for

positioning the glass in definite relation to the holder;

Fig. 6 is a sectional view illustrating a slightly modified form of disinfecting means.

Similar characters of reference designate corresponding parts throughout the several views.

The holder is conveniently attached to a wall or bracket and accordingly is shown as pendant from an attachment head 1 although some other means of support may, of course, be provided, if desired. The holder consists of a rod of metal, of suitable gage, fashioned into the required shape; and its active part is in the form of a relatively long and narrow upright U, comprising a pair of parallel members 1 and 2 and a curved bow 3 connecting their lower ends. The spacing of the members 1 and 2 is selected whereby the cylindrical wall of the glass may be readily inserted between them. When thus inserted between the members 1 and 2, the member 2 is disposed within the glass and the member 1 without, the glass resting with its edge upon the bow 3. The member 1 is provided with a guard 4 whose function is to hold the glass upright and in a definite or invariable relation; and said guard preferably comprises a transversely curved spring plate disposed symmetrically of the member 1 to which it is rigidly secured and presenting its concave side toward the glass. The said spring plate in fact provides a pair of wings located at opposite sides of the member 1 and which spring toward the glass and bear with frictional pressure thereon. By virtue of the guard 4 the glass will be held with practical security in a position wherein one of its diametrical planes will coincide with the common plane of the members 1 and 2.

The member 2 is provided at its upper end with a gooseneck extension 5 terminating in a pendant vertical arm 6 which is located in an extension of the plane common to the members 1 and 2 and, where the glass is of the size for which the holder is adapted, coincides or approximately coincides with the major central axis of the glass.

The arm 6 carries the disinfecting means at its lower end. As shown and preferred

said means comprises a container 7 for formaldehyde or some other suitable volatile disinfecting agent and a container 8 in which the container 7 is nested and which 5 maintains a supply of unslaked lime and water or equivalent elements to chemically develop heat and promote the evaporation of the volatile disinfecting agent. The container 7 constitutes a top closure for the 10 tainer 8 and is itself closed by a plate 9 threaded or otherwise detachably mounted on the lower end of the arm 6. The plate 9 is provided with a suitable number of apertures 10 for the escape of the vapor of 15 the liquid disinfectant and is utilized to support the container 8 for which purpose it is provided with an annular flange 11 having a sleeved relation to the container 8 and detachably connected thereto by bayonet 20 locks 12 or equivalent means. The plate 9 has a marginal portion which projects beyond the flange 11 and is formed to provide a series of holders 13 for tooth brushes or other dental implements whereby 25 the bristles of said brushes or the active parts of dental implements generally will be supported above the disinfecting means and will be subject to the action of the vapor of the disinfecting liquid. The container 8 30 preferably has its bottom 14 removable and held in position by bayonet locks 15 or equivalent devices. The removal of the bottom 14 promotes convenience in cleaning out the lime, when slaked.

35 The plate 9 is held above the margin of the glass and is located centrally of the glass whereby the vapor of the liquid disinfectant will circulate uniformly and with adequate strength over the exposed interior 40 surfaces of the glass and over the active parts of the implements in the holders 13 which said implements, being disposed within the glass, are at the same time protected against dust.

45 The heat developed by the slaking of the lime in the container 8 should have free access to the greater part of the external surfaces of the container 7 and for this purpose the container 7 may be conical, as 50 shown in Fig. 2, or it may be cylindrical but of less diameter than the container 8, as shown in Fig. 6.

Having described my invention and set forth its merits, what I claim is:

- 55 1. A holder for drinking glasses comprising a relatively long upright U shaped part having parallel members between which the cylindrical part of the glass may be inserted with one of said members inside and 60 the other outside of the glass, and means carried by one of said members to engage the glass and hold it in a position wherein one of its diametrical planes coincides with the common plane of said parallel members.
- 65 2. A holder for drinking glasses comprising

ing a relatively long upright U shaped part having parallel members between which the cylindrical part of the glass may be inserted with one of said members inside and the other outside of the glass, and a guard 70 carried by one of said members comprising a spring plate disposed transversely and symmetrically of the member by which it is carried and engaging the outer face of the glass with frictional pressure. 75

3. A holder for drinking glasses comprising a relatively long upright U shaped part having parallel members between which the cylindrical part of the glass may be inserted, one of said members having a goose 80 neck extension at its upper end, an arm pendant vertically from said extension and disposed to lie within the glass, and means supported at the lower end of said arm for maintaining a supply of volatile disinfect- 85 ing liquid.

4. A holder for drinking glasses comprising a relatively long upright U shaped part having parallel members between which the cylindrical part of the glass may be inserted with one of said members inside and the other outside of the glass, means carried by one of said members to engage the glass and hold it in a position wherein one of its diametrical planes coincides with the 90 common plane of said parallel members, and means carried by one of said members and disposed within the glass for maintaining a supply of volatile disinfecting liquid. 95

5. A holder for drinking glasses comprising a bracket-like fixture fashioned to support a drinking glass in an inverted position and provided with a pendant arm arranged for disposal within the glass and means provided at the lower end of said 100 arm for maintaining a supply of volatile disinfecting liquid. 105

6. A holder for drinking glasses comprising a bracket-like fixture fashioned to support a drinking glass in an inverted position and provided with a pendant arm for disposal within the glass, an apertured plate secured to the lower end of said arm and a receptacle for a volatile disinfecting liquid for which said plate provides a cover. 110

7. A holder for drinking glasses comprising a bracket-like fixture fashioned to support a drinking glass in an inverted position and provided with a pendant arm for disposal within the glass, an apertured plate 115 secured to the lower end of said arm, a receptacle for a volatile disinfecting liquid for which said plate provides a cover, and a second receptacle in which said first receptacle is nested and which is supported 120 by and pendant from said plate.

8. A holder for drinking glasses comprising a bracket-like fixture fashioned to support a drinking glass in an inverted position and provided with a pendant arm for 125 130

disposal within the glass, an apertured plate secured to the lower end of said arm and a receptacle for a volatile disinfecting liquid for which said plate provides a cover, said plate having its marginal portion formed to support tooth brushes or other dental implements.

In testimony whereof I affix my signature in presence of two witnesses.

FREDERICK E. SANDBURG.

ANNE E. CHAMPAGNE.

Correction in Letters Patent No. 1,276,419.

It is hereby certified that the name of the patentee in Letters Patent No. 1,276,419, granted August 20, 1918, for an improvement in "Holders for Drinking-Glasses," was erroneously written and printed as "Frederick E. Sandburn," whereas said name should have been written and printed as *Frederick E. Sanburn*; and that the said Letters Patent should be read with this correction therein that the same may conform to the record of the case in the Patent Office.

Signed and sealed this 8th day of October, A. D., 1918.

[SEAL.]

R. F. WHITEHEAD,

Acting Commissioner of Patents.
